[57] CLAIM

The ornamental design for a snowboarding boot sole, as shown and described.

DESCRIPTION

FIG. 1 is a left side view of a snowboarding boot sole according to this invention;

FIG. 2 is a right side view of the snowboarding sole of FIG. 1;

FIG. 3 is a front view of the snowboarding boot sole of FIG. 1;

FIG. 4 is a rear view of the snowboarding boot sole of FIG. 1; and,

FIG. 5 is a bottom view of the snowboarding boot sole, the undisclosed top forms no part of claimed design.

The broken line showing of environment in FIG. 1 is for illustrative purposes only and forms no part of the claimed design.
